UNITED STATES PATENT OFFICE

170,468

SOLDERING IRON BRUSH OR SIMILAR ARTICLE

Paul Le Ber, St. Hilaire, Quebec, Canada

Application March 6, 1953, Serial No. 23,941
In Canada January 14, 1953

Term of patent 7 years

(Cl. D9—2)

To all whom it may concern:

Be it known that I, Paul Le Ber, a French citizen, resident of St. Hilaire, Province of Quebec, Canada, have invented a new, original, and ornamental Design for a Soldering Iron Brush or Similar Article, of which the following is a specification, reference being had to the accompanying drawing, forming a part hereof, and wherein:

Fig. 1 is a front perspective view of the soldering iron brush or similar article, showing my new design.

Fig. 2 is a rear perspective view thereof.

I claim:

The ornamental design for a soldering iron brush or similar article, as shown.

PAUL LE BER.
